UNITED STATES PATENT OFFICE.

JOHN D. HUSSEY, OF WALTHALL, MISSISSIPPI.

DESIGN FOR A CLOTHES-POUNDER.

SPECIFICATION forming part of Design No. 32,134, dated January 23, 1900.

Application filed December 8, 1899. Serial No. 739,721. Term of patent 3½ years.

To all whom it may concern:

Be it known that I, JOHN DAVID HUSSEY, a citizen of the United States, residing at Walthall, in the county of Webster and State of Mississippi, have invented a new and useful Design for Clothes-Pounders, of which the following is a specification.

My invention relates to a design for clothes-pounders, which is illustrated in the accompanying drawings, in which—

Figure 1 is a side elevation of a pounder embodying my invention. Fig. 2 is an inverted perspective view of the same. Fig. 3 is a vertical central sectional view thereof.

My design consists of the funnel-shaped portion A, having extending downward therein a tubular portion B, the lower end of the tubular portion flared outwardly, as shown at a, the four wings b, which are situated between the tube B and the inner side of the funnel-shaped portion A, and the tubes d,

situated between the wings b and uniting the tube and the funnel-shaped portion A.

The essential features of my design are the arrangement of the four wings b, two of each of the four wings arranged in a straight line across the funnel-shaped portion A, and the four tubes d, which are similarly arranged, but situated between the said four wings.

Having thus described my invention, what I claim, and desire to secure by Letters Patent, is—

The design for a clothes-pounder substantially as herein shown and described.

In testimony whereof I have hereunto set my hand in the presence of two subscribing witnesses.

JOHN D. HUSSEY.
